UNITED STATES PATENT OFFICE.

FRANZ LÖSEL, OF BRUNN, CZECHOSLOVAKIA

ELASTIC-FLUID MULTISTAGE DISK-WHEEL TURBINE.

Original application filed August 14, 1923, Serial No. 657,375, and in Austria February 23, 1923. Divided and this application filed March 9, 1925. Serial No. 14,022.

This invention relates to elastic-fluid multi-stage disk-wheel turbines of the type which has separate carriers for the diaphragms arranged within an outer casing. 5 This application is a division of my co-pending application, Serial No. 657,375, filed August 14, 1923.

Arrangements have already been proposed in which the guide-bladings are not 10 directly connected to the casing, but to one or more carriers which are mounted within the casing, and are surrounded on all sides by the fluid. The devices of this kind heretofore used, however, have various disadvantages, particularly when high-pressure 15 and highly superheated steam is used.

It is an object of this invention to overcome these disadvantages and to improve and simplify the construction; to improve 20 the reliability; and to reduce the manufacturing costs of such turbines.

According to this invention, the guide-blading is combined in one or more groups, each of the groups comprising a number of 25 pressure-stages, built into one carrier, which is fitted steam-tight into the casing, the support for each separate group of diaphragms being formed, according to one construction, by one of the diaphragms itself, which is 30 fitted into the casing so that it makes a fluid-tight joint and carries other diaphragms of the group; and, according to another embodiment, the diaphragms are connected fluid-tight with the carriers by means of 35 separate milled blades or nozzles.

The nature of this invention and its advantages will be better understood by reference to the drawing, which will now be described; it being premised, however, that 40 changes may be made within the scope of the appended claims.

Figs. 1 and 2 of the accompanying drawings show two different embodiments of the invention applied to a high-pressure turbine, the figures representing longitudinal sections through the upper half of the turbine.

Referring at first to Fig. 1, it is shown that the annular diaphragm a' forms the 50 carrier for the other diaphragms a , and that the carrier portion for the diaphragms a is mounted within the outer casing g of the turbine by means of an annular projection, boss or rib z , which closely fits in a 55 fluid-tight manner, with its side walls, into

an annular groove f , formed in the inner wall of the casing, preferably between two annular projections f' . There is a radial clearance between the outer circumference of the boss or rib z and the corresponding 60 circumference of the cylindrical surface of the groove s . The diaphragms a of each group are fixed to the head or annular carrier portion of the diaphragm a' by means of bolts h and nuts or such like, which are 65 preferably sunk into corresponding cavities or recesses. In the embodiment of the invention shown in Fig. 1, two of such units, each comprising a group of three diaphragms, are arranged with a clearance-space 70 between them. The clearance-space communicates with an annular recess in the inner wall of the outer cylinder formed by the adjoining annular projections f' . e' designates the nozzles or guide passages in 75 the partitions or guide disks a_1 . These nozzles e' are located between the inner portion of the partitions a_1 and the outer carrier portion having the projection e^a designates the nozzles or guide passages in the 80 partitions a .

In the modified embodiment of the invention shown in Fig. 2, the diaphragm a' is connected by means of the nozzles e with an axially divided carrier, into which the 85 other diaphragms are fitted so as to make a fluid-tight joint.

Also in the modification of Fig. 2 the diaphragms a are connected with the axially divided carrier by means of the milled 90 blades e placed next to one another, thus enabling guiding nozzles to be produced which will act in an accurate and reliable manner.

The pressures of the driving fluid acting 95 in the spaces or fluid chambers between the carriers and outer casing are represented in the drawing by p , p' and p^2 , and it is evident that the fluid or steam surrounding the outside of the diaphragm carriers with its 100 pressures p and p' act to counter-balance the interior pressure, and also a very uniform distribution of the heat is secured within said carriers, so that deleterious influences of the heat and pressure are obviated, the high pressure differences being thereby removed from the diaphragms and carriers and the stresses and strains within the carriers due to heat and temperature 105 changes being kept away from the turbine 110

casing. Thereby, also, a very close fluid-tight fit of the diaphragms in the diaphragm carriers, and a close fit of the diaphragm carriers within the casing, are secured, and leakages prevented, although provision is made for all expansion due to heat. Hence, the arrangement, according to the invention, is especially suitable for turbines operating with highly superheated steam under high steam pressure. Each separate set of diaphragms carried by its carrier member forms a distinct partition in the turbine and the working fluid is forced to flow through the nozzles of the set and not around the same. The diaphragms carried by the carrier body form partitions within said carrier groups for the stages of said groups.

It will be understood by those skilled in the art that the embodiments shown in the drawings as above described are only illustrative, and that they do not restrict the invention to these embodiments. For example, instead of two carriers, any number of carriers may be arranged within the outer casing, and each carrier may contain more or less than three diaphragms; or, instead of making one of the axially divided diaphragms part of the carrier, the diaphragms including their nozzles may be carried in any suitable manner by the carriers.

Claims:

1. In an elastic-fluid turbine of the multi-stage disk-wheel type, an outer casing having an annular groove in an inwardly projecting annular part, diaphragms including nozzles and spaced inwardly from the outer casing, at least one inner cylindrical casing or carrier connected with said diaphragms and having an annular projection to fit into said groove in the outer casing and form a fluid tight connection and providing at each side of the connection clearance spaces between the inner casing and the outer casing.

2. In an elastic fluid multi-stage disk-wheel turbine, guide disks, separate carriers for the guide disks, each carrier containing a group of disks, one of which is formed integral with its carrier, while the other guide disks form separate pieces connected with said carrier, and an outer casing, the connection between the carrier and the outer casing being made by a boss or rib outside of the carrier, and a corresponding groove in the inner wall of the outer casing, a clearance-space being provided between the outer circumference of said rib and the cylindrical face of said groove, but said connection being fluid tight.

3. An elastic-fluid turbine of the multi-stage disk-wheel type comprising an outer casing, diaphragms arranged in sets and including nozzles or guide passages, and carriers for said sets of diaphragms mounted in said outer casing in a fluid tight and

radially adjustable manner and so positioned and shaped as to provide separate fluid chambers between the outer casing and the carriers and clearance spaces between successive sets of diaphragms, said carriers and the corresponding groups of diaphragms, forming partitions in the turbine, the diaphragms in each group forming partitions in the group, said groups being free at both ends.

4. An elastic-fluid turbine of the multi-stage disk-wheel type, comprising an outer casing, guide disks grouped in sets, inner carriers for said sets of guide disks, each carrier being integral with one of the guide disks of the corresponding set and mounted in said outer casing in a fluid tight manner, and so shaped and positioned as to provide spaces between the outer casing and the carriers and between the carrier-sets, adapted for receiving elastic fluid from the entrance side and outlet side of each carrier-set, to cause said elastic-fluid to surround the carriers and associated guide disks.

5. An elastic fluid turbine of the multi-stage disk wheel type comprising an outer casing, guide disks grouped in sets and carriers for said sets of guide disks, mounted in said outer casing in a fluid tight manner, and so positioned and shaped as to provide spaces between the outer casing and the carriers and between the carrier-sets adapted for receiving elastic-fluid from the entrance side and outlet side of each carrier-set to cause said elastic fluid to surround the carriers and associated guide disks, each carrier mounted in the outer casing being formed integral with one of the guide disks of each set which is connected in a steam-tight manner with the other guide disks in each set.

6. A high pressure elastic fluid multi-stage disk wheel turbine having a separate carrier member for the diaphragms carrying the guide nozzles disposed within and supported from the turbine casing member, one of said members being provided with a connecting groove and the other being provided with a corresponding connecting rib which forms the supporting connections for the carrier, a clearance space being provided between the rib and the bottom of said groove to provide for relative radial movement between the two members, said carrier forming with the turbine casing a steam chamber about its high pressure end which is in communication with the steam at the entrance side of the guide nozzles and said groove-rib supporting connection forming a barrier to the steam in the chamber.

7. An elastic fluid turbine of the multi-stage disk-wheel type, comprising an outer casing, guide-disks including guide nozzles for the fluid flow grouped in sets, and radially adjustable carrying means for said sets

of guide-disks mounted in said outer casing in a fluid-tight manner and so positioned, shaped and connected with the guide-disks as to provide spaces between the outer casing and the carrying means and between such guide-disk sets adapted for receiving elastic fluid from the entrance side and outlet side of adjacent guide-disk sets to cause said elastic fluid to substantially surround the carrying means and associated guide-disks, and said nozzles, which provide the guide-passages in the guide-disks, being located between said carrying means mounted in the outer casing and the inner portions of the guide-disks.

8. An elastic-fluid turbine of the multi-stage disk-wheel type, comprising an outer casing, guide-disks grouped in sets, and radially adjustable carrying means for said sets of guide-disks mounted in said outer casing in steam-tight manner and so positioned, shaped and connected with the guide-disks, as to provide spaces between the outer casing and the carrying means and between the guide-disk sets adapted for receiving an elastic-fluid from the entrance side and the outlet side of each guide-disk set to cause said elastic fluid to substantially surround the carrying means and associated guide-disks having nozzles therearound which provide the guide-passages between the guide-disks and the carrying means.

9. In an elastic-fluid turbine of the multi-stage disk-wheel type, an outer casing, and a set of guiding-disks exposed on all sides to the pressure of elastic fluid and including one guiding-disk mounted in the casing in a fluid-tight manner and providing supporting means for the other guide-disks and spaced from the inner surface of the casing.

10. In a multistage turbine of the disk-wheel type, an outer casing, a set of guiding disks exposed on all sides to the pressure of the elastic fluid and including one guiding-disk mounted in the casing in a fluid-tight manner and providing supporting means for the other guiding disks, and separate blades assembled in rows to form the guide-passages at the peripheries of guide-disks and serving as connections between the supporting guiding-disk and the other disks.

11. In an elastic fluid turbine of the multi-stage disk-wheel type, an outer casing, an element including a diaphragm, nozzles and an outer carrier portion connected with the outer casing, and other diaphragms and corresponding nozzles supported by said carrier portion.

12. In an elastic fluid turbine, an outer casing, a diaphragm including nozzles and an outer carrier portion connected with the outer casing and serving as a partition in said turbine, and other diaphragms and corresponding nozzles supported by said carrier portion.

13. In an elastic fluid turbine, an outer casing, a set of diaphragms, one of said diaphragms being connected with the outer casing and forming therein a partition carrying the other diaphragms of said set. 70

14. In an elastic fluid turbine, an outer casing and a set of diaphragms, one of said diaphragms carried by the outer casing and forming a partition having a fluid-tight connection with said outer casing and the other 75 diaphragms of said set being spaced from said outer casing, carried by said partition and forming fluid-tight connections therewith.

15. In an elastic fluid turbine, an outer 80 casing, an element including a diaphragm and nozzles forming a partition in said outer casing, and a plurality of other diaphragms including nozzles having a fluid-tight connection with said element and forming there- 85 with a separate independent diaphragm set enclosed by said outer casing but spaced therefrom to form fluid chambers therearound.

16. In an elastic fluid turbine, an outer 90 casing, an element including a diaphragm and nozzles forming a partition in said outer casing, a plurality of other diaphragms including nozzles carried by said element and forming with the same a separate independent 95 diaphragm group enclosed by said outer casing but spaced therefrom to form fluid chambers therearound, and a fluid-tight connection with a radial clearance between said element and outer casing. 100

17. In an elastic fluid turbine, an outer casing, a diaphragm including nozzles and an outer portion connecting with the outer casing and serving as a partition in said turbine and as a carrier for other diaphragms and corresponding nozzles, and other diaphragms carried by said element 105 partitions within said element.

18. An elastic-fluid turbine of the multi-stage disk-wheel type comprising an outer 110 casing, guide-disks or diaphragms including nozzles and arranged in groups with one diaphragm of each group serving as a carrier for the other diaphragms of such groups, provision being made of fluid chambers or 115 spaces between the outer casing and the diaphragm groups and between such groups to receive elastic fluid in the turbine, said groups being independent of each other and forming partitions in the turbine and the diaphragms of said groups forming partitions within said group. 120

19. In an elastic fluid multi-stage disk-wheel turbine, guide-disks, separate carriers for the guide-disks, each carrier containing 125 a group of disks, one of which is formed integral with the carrier, while the other guide-disks form separate pieces connected with said carrier, and an outer casing, said carrier being connected with the outer cas- 130

- ing by means of abutting surfaces in a fluid-tight manner but provision being made at the connection to allow radial expansion of the carrier.
20. In an elastic fluid turbine of the multi-stage disk-wheel type, a diaphragm connected with an outer casing, forming a partition for a group of stages, carrying a plurality of diaphragms including nozzles for said stages and forming therewith a separate rotor enclosing diaphragm group, said diaphragm group being subjected to different fluid pressures at the entrance and leaving side thereof corresponding to the different fluid pressures at the entrance and leaving side of said diaphragm group.
21. In an elastic fluid turbine of the multi-stage disk wheel type, an outer casing, and an element including a partition, nozzles and an outer portion connecting with said outer casing but spaced therefrom, said element serving as a carrier for a plurality of partitions including nozzles for a plurality of stages and forming with said element a separate rotor enclosing diaphragm group which is subjected to different pressures at the entrance and leaving side thereof corresponding to the different fluid pressures at the entrance and leaving side of said diaphragm group.
22. An elastic fluid turbine of the multi-stage disk wheel type comprising a main casing, at least one high pressure disk wheel disposed at the inlet end of the casing, a group of disk wheels of smaller diameter immediately following but spaced from said first named wheel, a corresponding group of stationary guide disks for said group of disk
- wheels, and a radially movable carrier for said guide disks supported within the main casing and spaced therefrom to form therebetween a steam chamber communicating with one side of said high pressure wheel.
23. An elastic fluid turbine of the multi-stage disk wheel type comprising a main casing, at least one high pressure disk wheel disposed at the inlet end of the casing, a group of disk wheels of smaller diameter immediately following but spaced from said first named wheel, a corresponding group of stationary guide disks for said group of disk wheels, and a radially movable carrier for said guide disks supported within the main casing and spaced therefrom to form therebetween a steam chamber communicating with said high pressure wheel, the first stationary guide disk of said group forming with the high pressure wheel a steam chamber communicating with the chamber surrounding the carrier.
24. A turbine of the character set forth in claim 22 wherein the high pressure wheel has a diameter approximating the diameter of the separate carrier for the group of diaphragms.
25. A turbine of the character set forth in claim 22 wherein the cylindrical carrier for the diaphragms is supported from the main casing by a fluid tight connection intermediate its ends and is spaced from the main casing so as to form steam chambers surrounding the carrier on the opposite sides of said connection.

In testimony whereof I affix my signature.

- ing by means of abutting surfaces in a fluid-tight manner but provision being made at the connection to allow radial expansion of the carrier.
20. In an elastic fluid turbine of the multi-stage disk-wheel type, a diaphragm connected with an outer casing, forming a partition for a group of stages, carrying a plurality of diaphragms including nozzles for said stages and forming therewith a separate rotor enclosing diaphragm group, said diaphragm group being subjected to different fluid pressures at the entrance and leaving side thereof corresponding to the different fluid pressures at the entrance and leaving side of said diaphragm group.
21. In an elastic fluid turbine of the multi-stage disk wheel type, an outer casing, and an element including a partition, nozzles and an outer portion connecting with said outer casing but spaced therefrom, said element serving as a carrier for a plurality of partitions including nozzles for a plurality of stages and forming with said element a separate rotor enclosing diaphragm group which is subjected to different pressures at the entrance and leaving side thereof corresponding to the different fluid pressures at the entrance and leaving side of said diaphragm group.
22. An elastic fluid turbine of the multi-stage disk wheel type comprising a main casing, at least one high pressure disk wheel disposed at the inlet end of the casing, a group of disk wheels of smaller diameter immediately following but spaced from said first named wheel, a corresponding group of stationary guide disks for said group of disk
- wheels, and a radially movable carrier for said guide disks supported within the main casing and spaced therefrom to form therebetween a steam chamber communicating with one side of said high pressure wheel.
23. An elastic fluid turbine of the multi-stage disk wheel type comprising a main casing, at least one high pressure disk wheel disposed at the inlet end of the casing, a group of disk wheels of smaller diameter immediately following but spaced from said first named wheel, a corresponding group of stationary guide disks for said group of disk wheels, and a radially movable carrier for said guide disks supported within the main casing and spaced therefrom to form therebetween a steam chamber communicating with said high pressure wheel, the first stationary guide disk of said group forming with the high pressure wheel a steam chamber communicating with the chamber surrounding the carrier.
24. A turbine of the character set forth in claim 22 wherein the high pressure wheel has a diameter approximating the diameter of the separate carrier for the group of diaphragms.
25. A turbine of the character set forth in claim 22 wherein the cylindrical carrier for the diaphragms is supported from the main casing by a fluid tight connection intermediate its ends and is spaced from the main casing so as to form steam chambers surrounding the carrier on the opposite sides of said connection.

In testimony whereof I affix my signature.
